UNITED STATES PATENT OFFICE

127,159

DESIGN FOR A TANDEM WING MONOPLANE

Leo E. Oliver, Sanger, Calif.

Application December 23, 1940, Serial No. 97,564

Term of patent 14 years

To all whom it may concern:

Be it known that I, Leo E. Oliver, a citizen of the United States, residing at Sanger, county of Fresno, State of California, have invented a new, original, and ornamental Design for a Tandem Wing Monoplane, of which the following is a specification, reference being had to the accompanying drawing, forming a part thereof.

In the drawing:

Figure 1 is a top plan view of a tandem wing monoplane showing my new design.

Figure 2 is a side elevational view of the monoplane.

Figure 3 is a front end elevational view of the same.

I claim:

The ornamental design for a tandem wing monoplane, as shown.

LEO E. OLIVER.
